The ornamental design for a storage basket, as shown and described.

DESCRIPTION

FIG. 1 is a top, front, left perspective view of a storage basket showing my design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof;

FIG. 7 is a bottom plan view thereof;

FIG. 8 is a detail view of FIG. 6; and,

FIG. 9 is a detail view of FIG. 7.

The broken lines in the figures depict portions of the storage basket that form no part of the claimed design. The longer dashed lines in FIGS. 6-9 depict circumscribed enlarged details and form no part thereof.
